United States Patent Office.

JAMES ALLINSON, OF PHILADELPHIA, PENNSYLVANIA, ASSIGNOR TO JOHN BROMLEY AND SONS, OF SAME PLACE.

Design No. 3,143, dated August 4, 1868.

DESIGN FOR CARPET-PATTERN.

The Schedule referred to in these Letters Patent and making part of the same.

TO ALL WHOM IT MAY CONCERN:

Be it known that I, JAMES ALLINSON, of the city and county of Philadelphia, in the State of Pennsylvania, have invented a new and ornamental Design for a Carpet-Pattern; and I do hereby declare that the accompanying photographic representation fully exhibits my said design.

What I claim as new, and desire to secure by Letters Patent, is—

The design or pattern for carpets herein set forth and shown.

To the above I have signed my name, this twenty-ninth day of June, 1868.
